UNITED STATES PATENT OFFICE

ARTHUR R. McARTHUR, OF GARY, INDIANA, AND HOWARD G. McILVRIED, OF Mc-
CANDLESS TOWNSHIP, ALLEGHENY COUNTY, PENNSYLVANIA, ASSIGNEES TO
AMERICAN SHEET AND TIN PLATE COMPANY, OF PITTSBURGH, PENNSYLVANIA,
A CORPORATION OF NEW JERSEY

HEATING FURNACE

Application filed January 24, 1928. Serial No. 249,147.

This invention relates to heating furnaces and, while not limited thereto, relates more particularly to continuous heating furnaces for heating sheets and packs of sheets, and 5 has for one of its objects the provision of a furnace of this class having a combustion chamber separate from and along the one side of the heating chamber, so as to provide a chamber in which tar and soot will deposit 10 when burning raw producer gas.

Another object is to provide a novel form of combustion port between the combustion and heating chambers, and a novel form of roof over both of said chambers whereby the 15 products of combustion will have a centrifugal force imparted to them as they pass into said heating chamber.

A further object is to provide a furnace of this class having a novel form of conveying 20 means whereby the sheets will be conveyed through the furnace at varying speeds at different points in the length of the furnace.

In the drawings—

Figure 1 is a sectional plan of a furnace 25 constructed in accordance with this invention.

Figure 2 is a side elevation, the right-hand half of which is sectioned on the line II—II of Figure 1.

Figure 3 is a sectional side elevation taken 30 on the line III—III of Figure 1.

Figure 4 is a transverse sectional elevation taken on the line IV—IV of Figure 1.

Figure 5 is a rear end elevation.

Referring more particularly to the drawings, the numeral 2 designates the heating chamber and the numeral 3 designates the combustion chamber of the furnace. The 35 walls of the furnace are of usual construction and are composed of brick with the usual steel supporting structure X. The one side wall 4 of the furnace is offset horizontally, as at 5, and then continued upwardly, as at 6, for the greater portion of its length to 40 form the combustion chamber 3. A partition wall 7 is built up on the horizontal offset portion 5 of the side wall 4 in line with the lower portion of said wall and serves to 45 separate the heating and combustion chambers. 50

The side wall 8 opposite the side wall 4 is a straight, vertical wall and is of materially less height than the wall 4. A transversely curved or arched roof 9 extends from the top of the side wall 4 to the top of the wall 8 and has the highest point of its curve or arch over or adjacent to the partition wall 7. 55

The partition wall 7 is cut away in step formation of progressively less depth from the rear or burner end of the furnace forwardly to form a port 10 through which the products of combustion are discharged into the heating chamber. The port 10 may extend along the entire length of the wall 7, as shown, or may terminate short of the forward end, as desired. 60

A burner 12 is mounted in the rear end wall 14 of the furnace so as to deliver products of combustion to the combustion chamber 3. 65

The heating chamber is provided with an inlet opening or port 15 in the rear end wall 14, and with an outlet or discharge opening or port 16 in the forward end wall 17, to provide for the inlet and discharge of the sheets, 70 respectively. 75

A vertical flue 18 is mounted on the outer face of the forward end wall 17 and is adapted to receive the products of combustion escaping through the discharge opening or port 16 of the heating chamber. The flue 18 has an open lower end and has its upper end connected by a conduit 19 with a stack 20. 80

A preheater unit 20^a is mounted in the flue 18 and is adapted to preheat the air supplied to the burner 12. This preheater unit 20^a is not a part of the present invention, and will be made the subject matter of a separate application for patent. Therefore, it will not be described nor shown in detail. 85

A series of conveyer rollers 22 of the disk type are arranged transversely in the heating chamber 2 and have their shafts 23 projecting through the side walls of the furnace and journaled in bearings 24 mounted on the steel supporting structure X. A short drive-shaft 26 is connected to each of the roller-shafts 23 by a flexible coupling 27. 90

A main drive-shaft 28 extends longitudinally along the one side of the furnace and 100

is journaled in suitable bearings on a stand support 29.

The drive-shafts 26, connected to all the roller-shafts 23 from the rear end of the furnace forwardly to within a short distance from the forward end of the furnace, are provided with worm-wheels 30 which are meshed with worms 31 on the main drive-shaft 28, and the remainder of the shafts 26, up to and including the foremost shaft 26, are provided with spiral gears 32 which are in mesh with spiral gears 33 on the main drive-shaft 28.

A spur gear 34 is provided on the rear end of the main drive-shaft 28 which is in mesh with a pinion 35 on the armature-shaft of a drive-motor 36. The circuit to the motor 36 is adapted to be controlled by the roller to which the sheets being heated are to be delivered, and since any usual form of standard controller may be used for this purpose, no illustration is made of this element.

In operation, the furnace will be preferably fired with raw producer gas and the gas will be partly consumed or burned in the combustion chamber 3. The partly burned gases and products of combustion will pass from the combustion chamber 3 through the port 10 into the heating chamber 2.

When raw producer gas is burned, especially when the combustion is incomplete, as is essential in the present instance in order to maintain a non-oxidizing atmosphere in the heating chamber 2, the burning gas will deposit tar and soot particles. The combustion chamber 3 serves to trap the tar and soot deposits from the burning gas in the furnace of this invention and thereby prevents the deposits of tar and soot from being deposited on the metal being heated.

Due to the curved or arched form of the roof 9, the partly burned gases and products of combustion, when passing from the combustion chamber 3 to the heating chamber 2, will have a centrifugal force imparted thereto which, coupled with the normal forwardly projecting force produced by the burner 12, will cause the flame and products to assume a forwardly traveling swirling motion through the heating chamber so as to pass over and under the sheets being heated.

The major portion of the flame and products of combustion will pass from the combustion chamber at the rear or largest end of the port 10 so as to cause a crowding of the flame at this end and thereby force a small amount of flame to pass through the inlet port 15 of the heating chamber. The passing of this small amount of flame through the inlet port 15 is essential in order to block this port and prevent the ingress of cold air through the open port.

The heating chamber 2 will be filled with the flame and products of combustion for its entire length although the flame will be hotter near the rear or inlet of the furnace

than at the forward or exit end. By providing the hottest zone of the heating chamber 2 adjacent its rear or inlet end where the sheets are cold, scaling of the sheets is prevented since the cold sheets will take up the heat readily without scaling.

The flame and products of combustion will pass from the furnace through the discharge or exit port 16 and, due to the draft in the flue 18, will pass into this flue and to the stack.

When the furnace is heated sheets or packs of sheets will be passed into the rear end of the heating chamber 2 through the inlet opening or port 15 and will be conveyed through the furnace by the rollers 22.

The worm driven rollers will be rotated at a materially slower speed than the spiral gear driven rollers at the forward end of the heating chamber, so that the sheets will travel slowly through the major length of the heating chamber and be heated, then will be delivered with considerable speed and force from the discharge or forward end of the furnace.

The furnace will be under the control of the roller receiving the heated sheets and he will close the circuit to the motor 36 so as to operate the rollers 22 when he desires a sheet or pack of sheets only.

In view of this, it will be understood that the sheets will be moved with a step-by-step movement through the furnace.

It will, of course, be understood that we do not wish to limit our invention to this step-by-step movement since the furnace may be so timed that the sheets may move continuously through the furnace without interruption.

While we have described certain specific embodiments of our invention, we do not wish to be limited thereto since various modifications may be made without departing from the scope of our invention, as defined in the appended claims.

We claim—

1. A continuous heating furnace for heating sheets and packs of sheets comprising an elongated heating chamber having an entrance port in one end and a discharge port in the other end, a combustion chamber along one side of said heating chamber and separated therefrom for at least a part of its length by a partition wall, an elongated port formed above said partition wall for at least a part of its length, said port being reduced in area from the entrance end toward the discharge end of the furnace, and a source of combustibles at the entrance end of said combustion chamber.

2. A continuous heating furnace for heating sheets and packs of sheets comprising an elongated heating chamber having an entrance port in one end and a discharge port in the other end, a combustion chamber along

- one side of said heating chamber and separated therefrom for at least a part of its length by a partition wall, an elongated port formed above said partition wall for at least 5 a part of its length, said port being reduced in area from the entrance end toward the discharge end of the furnace, a burner at the entrance end of said combustion chamber, the products of combustion being adapted to pass 10 through said elongated port into said heating chamber and to travel longitudinally of said heating chamber and escape through said discharge port, and means for conveying the sheets through said heating chamber. 15 3. A continuous heating furnace for heating sheets and packs of sheets comprising an elongated heating chamber having an entrance port in one end and a discharge port in the other end, a combustion chamber 20 along one side of said heating chamber and separated therefrom for at least a part of its length by a partition wall, an elongated port formed above said partition wall for at least a part of its length, said port being reduced 25 in area from the entrance end toward the discharge end of the furnace, a burner at the entrance end of said combustion chamber, and a curved roof wall extending over both of said chambers, said wall having its highest 30 point over said partition wall. 4. A continuous heating furnace for heating sheets and packs of sheets comprising an elongated wide heating chamber having an entrance port in one end and a discharge 35 port in the other end, a narrow combustion chamber along one side of said heating chamber and separated therefrom for at least a part of its length by a partition wall, an elongated port formed along the top of said 40 partition wall for at least a part of its length through which the products of combustion pass into said heating chamber, said port being reduced in area from the entrance end toward the discharge end of the furnace, a 45 burner at the entrance end of said combustion chamber, and a transversely curved roof wall extending over both of said chambers, said wall having its highest point over said partition wall and being adapted to impart 50 a centrifugal whirl to the products of combustion as they pass into said heating chamber. 5. A continuous heating furnace comprising an elongated heating chamber having entrance and discharge ports, a combustion chamber along one side of said heating chamber and of materially shorter length than said heating chamber, said combustion and heating chambers being separated for at least 55 a part of their length by a partition wall, an elongated port formed above said partition wall for at least a part of the length of said wall, said port being reduced in area from one end toward the other end of said combustion chamber, and a source of combus- 60 65
- tibles at the end of said combustion chamber having the greatest port area. In testimony whereof, we have hereunto set our hands.
